772X

Glover & Parmelee,
Mortising Machine.

Patented June 8, 1807.

Fig: 1

Simon Glover and David Parmenter

Letters Patent Pat'd. June 8th 1807.

The schedule or specification in these Letters Patent and making part of the same, containing a description in the words of the said Simon Glover and David Parmenter themselves of their Machine for Mortising.

The Mortising Machine is a chisel with teeth in the fore side of it. This chisel is forced back and forth, or up & down (by a lever) through the timber or material to be mortised; and when crowded forward it cuts the mortise. The lever is moved backward and forward, or up & down, by manual, animal or fluid power.

The principle of this Machine is to facilitate the labour & accelerate the making of Mortises by a chisel, that is put in motion by a lever, which lever is put in motion by manual animal or Fluid Power.

The effect is, Mortises are made easier, quicker & more joint
